Gifford & Ball

ATTORNEY.

UNITED STATES PATENT OFFICE.

HENRY L. G. GERSTENBERGER, OF ROSELLE, NEW JERSEY, ASSIGNOR, BY MESNE ASSIGNMENTS, TO STANDARD DEVELOPMENT COMPANY, A CORPORATION OF DELAWARE.

BUNG.

Application filed August 5, 1919. Serial No. 315,402.

To all whom it may concern:

Be it known that I, HENRY L. G. GERSTENBERGER, a citizen of the United States, residing at Roselle, in the county of Union and State of New Jersey, have invented certain new and useful Improvements in Bungs, of which the following is a specification:

Barrels which are to act as containers for petroleum are usually subjected on the interior to a gluing treatment prior to being filled with the liquid. The glue is placed in the barrel, the barrel closed by a temporary bung, and the barrel is then rotated, usually mechanically, and the glue forms one of the coatings necessary to prevent the petroleum from leaking through the staves of the barrel. At the same time, gases are formed within the barrel, which create a pressure sufficient to expel glue through any openings, such as worm holes, and thus a test for leaks in the barrel is afforded. The temporary bungs which have hitherto been used have proved unsatisfactory, for the reason that they are frequently expelled from the barrels, particularly after they have been in use for some time, with the consequence that the operating room soon becomes unsanitary, and particularly so because of the well known, objectionable qualities of glue.

My invention has for its object the provision of a bung which is not expelled from the barrel under the conditions indicated above, and while the bung is of general application and not limited in its use to situations of this character, it is particularly applicable to such use.

Referring, now, to the drawings, in which I have shown one embodiment of my invention, Fig. 1 is a sectional view of a portion of a stave provided with a bung-hole in which a bung embodying my invention is shown in position, in side elevation; Fig. 2 is a sectional view through the bung and the support therefor, and showing the bung in its natural extended condition, and Fig. 3 is a similar sectional view at right angles to Fig. 2, and showing the bung slightly compressed and its horizontal diameter correspondingly increased.

Referring, now, to the drawings, in which like reference characters indicate like parts, 10 is a bung, hollow and globular in form and made of a flexible, yielding material, such as rubber. In practice, I have found

that the bung may conveniently be made about one-eighth of an inch in thickness, though obviously this thickness may be varied as conditions may require. The bung 10 engages a concave seat 11 formed in a support 12. The support is preferably cored out, as at 13, in order to reduce the weight thereof, and is preferably provided at its middle portion with a boss 14, in which is received a stem 15, and which, in the embodiment of my invention here illustrated, is secured to the boss in any desired manner. The stem 15 passes through openings 17 and 18 formed in the opposite sides of the globular member 10. A washer 19, provided with a concave seat to engage the ball 10, surrounds the stem 15 and is clamped against the globular member 10 by a nut 20 which is secured to the end of the stem 15.

In order to secure the bung in the substantially circular bung-hole of a barrel, the bung is placed in position within the hole, the nut 20 is then screwed home until the globular member 10 is compressed to such an extent, and its diameter thereby increased to such an extent, that it will tightly fit the bung-hole. The operator then places the globular member in the bung-hole, as indicated at 21 in Fig. 1, in the stave 22 and imparts to the supporting member a sharp blow, when the bung will assume the position shown in Fig. 1 and the globular member will engage the walls of the bung-hole when the bung has been properly adjusted, with sufficient friction to prevent its being expelled during the gluing operation, the rubber or similar material of which the bung is preferably formed being well adapted to make good frictional engagement with the walls of the bung-hole, the bung being preferably constructed and arranged to engage, at its greatest diameter, the wall surrounding the bung opening at a point or line intermediate the edges of the opening, as shown in Fig. 1. It will, of course, be apparent that the diameter of the bung 10 may be varied, within certain limits, to accommodate itself to different size bungs, such as may result, for example, when barrels have been used for some time.

What I claim and desire to secure by Letters Patent of the United States is:

1. A globular bung formed of flexible material, a support for the bung formed with a

concave seat, and associated means for varying the diameter of the bung.

2. A hollow globular bung formed of flexible material, a support for the bung formed with a concave seat for the bung, and associated means for varying the diameter of the bung.

3. A hollow globular bung formed of flexible yielding material, a support therefor formed with a concave surface within which the bung is adapted to be seated, a stem projecting through the bung and adapted to be secured to said support, and means for engaging the stem for compressing the bung and thereby varying the diameter thereof.

4. A bung comprising a hollow globular ball formed of yielding material and arranged to be inserted in the bung-hole of a barrel, a support for the bung formed with

a concave surface within which the bung is seated, a stem projecting from said support through the bung, a washer received on said stem and engaging the bung on the opposite side from the support, and a nut threaded to said stem and engaging said washer for varying the diameter of said bung.

5. A bung comprising a hollow globular rubber ball and arranged to engage a bung-hole of a barrel, a support for the bung formed with a concave surface within which the bung is seated, a stem projecting from said support through the bung, a washer received on said stem and engaging the bung on the opposite side from the support, and a nut threaded to said stem and engaging said washer for varying the diameter of said bung.

HENRY L. G. GERSTENBERGER.
